Primary Examiner — W. A. Teddy Falloway*Assistant Examiner* — Amanda Kay Birdwell(74) *Attorney, Agent, or Firm* — James E. Piotrowski(57) **CLAIM**

The ornamental design for a bottle, as shown.

DESCRIPTION

FIG. 1 is a perspective view of a bottle embodying my new design;

FIG. 2 is a front side, elevational view thereof;

FIG. 3 is a rear side, elevational view thereof;

FIG. 4 is a right side elevational view thereof;

FIG. 5 is a left side elevational view thereof;

FIG. 6 is a bottom plan view thereof; and,

FIG. 7 is a top plan view thereof.

Any dotted lines shown in the accompanying drawings are intended to illustrate environmental features not intended to be a part of the claimed drawing in the figures in which they appear.

1 Claim, 6 Drawing Sheets(56)
